UNITED STATES PATENT OFFICE.

WILLIAM H. COLLIER, OF JACKSON, TENNESSEE.

CHANGE-MAKING CASH-REGISTER.

No. 823,104.

Specification of Letters Patent.

Patented June 12, 1906.

Application filed June 20, 1902. Serial No. 112,441.

To all whom it may concern:

Be it known that I, WILLIAM HENRY COLLIER, a citizen of the United States, and a resident of the city of Jackson, in the county of Madison and the State of Tennessee, have invented a certain new and useful Change-Making Cash-Register, of which the following is a specification.

The several features of my invention and the various advantages of their use, conjointly or otherwise, will be apparent from the following description and claims.

In the accompanying drawings, making a part of this specification and to which reference is hereby made, Figure 1, Sheet 1, is a front elevation of the machine with a part of the outside casing removed. Fig. 2, Sheet 2, is an end elevation of the machine, the outside casing having been removed. Fig. 3, Sheet 3, represents the mechanism for making change, which includes the base of the change-making tubes and accompanying mechanism as viewed from underneath said base. Fig. 4, same sheet, is a vertical longitudinal central section of the mechanism shown in Fig. 3. Fig. 5, Sheet 4, is a view of a portion of the mechanism for operating the devices which control the delivery-orifices of the tube T^{100} , containing the dollars. Fig. 5^a, same sheet, is a section through arms R^3 and R^4 . Fig. 6 is an end view of the mechanism which controls the delivery-orifices of T^{100} . Fig. 7 of same sheet is a view in perspective of those ends of the segments V^2 and V^3 and of disk V which are shown in Figs. 5 and 6. Fig. 8, Sheet 3, is a sectional view taken through coin-tube T^{25} , showing section of bar which supports coin-tubes and slides which control same. Fig. 9, Sheet 5, is a vertical section taken through center of machine. Fig. 10, same sheet, is a horizontal section taken through machine below coin-tube supports. Fig. 11, Sheet 6, is a plan of the machine, with top casing and the tubes containing coins and their supports removed. Fig. 12, Sheet 7, is a view of the arc which controls the orifice of tube T^5 . Fig. 13, same sheet, is a view of the arc which controls the orifice of tube T^{10} . Fig. 14, same sheet, is a view of the arc which controls the orifice of T^{25} and has ratchet-teeth on lower periphery, which is engaged by pawl attached to top of frame. Fig. 15, same sheet, is a view of the arc that controls orifice of tube T^{50} . Fig. 16, same sheet, is a view of cams which are fixed

to same shaft S^2 . Fig. 17, same sheet, is a sectional view through Fig. 16 at S.

The mechanism for making change is substantially as follows: Finger-levers C are present for setting change-making mechanism. Each lever has a distinctive number marked thereon to be used in registering the amount of sale and to set the mechanism in position for making change and to operate the indicator. These numbers are to be varied in different machines to be especially useful for large or small sales, according as the operator desires. In the present illustrative instance the levers are marked from "no sales," increasing by five cents until a dollar is reached, and then from a dollar by dollars to five dollars. These levers are loosely pivoted on a fixed shaft S. On the rear portion of each lever is a pin P, Figs. 2 and 16. Each pin has an individual cam G, which it operates. Each cam is set in a given position on a rotatable shaft S^2 , so as to properly operate the mechanism for holding or dropping the change, so as to enable the lever C to hold or drop the change for which it stands. The cam G is illustrated in Fig. 16, the lower face G^2 being the operating-face, which meets the adjacent pin P. The hook G^3 is to prevent the pin P from leaving the cam. All of the cams G are of the same shape, but are adjusted at different angles on the shaft as are necessary to perform their respective functions. This shaft S^2 carries governing-arcs H, Figs. 4, 12, 13, and 14, and 15 to hold or release horizontal slides B, Fig. 4. Each arc H is connected by an arm H^7 rigidly to the shaft S^2 and is set at its proper angle relatively to the shaft S^2 . (See Sheets 1, 2, and 7.) There should be in the present instance four of these arcs H, to coöperate, respectively, in the feeding of fifty-cent, twenty-five-cent, ten-cent, and five-cent pieces. The dollars are operated by means of the revolving arms R^4 and R^5 . The entire operative mechanism carried by the shaft S^2 is balanced by a counterweight or other suitable device connected thereto. In this instance the lower or segmental part of governing device or arc is used for that purpose.

The arc H is constructed as follows: Take, for example, the arc for assisting in feeding five-cent pieces, Fig. 12. The periphery H^4 of the arc is theoretically divided into twenty-one equal divisional parts, these parts being each equal to the width of lug B^2 of slide B,

Sheet 3, the second, third, fifth, seventh, eighth, tenth, twelfth, thirteenth, fifteenth, seventeenth, eighteenth, and twentieth having slots H^3 , the rest being solid. The first 5 division (indicated in Fig. 12 by 1) is the position it assumes with reference to B^2 after change has been made. The point indicated by 2, or the second division, is the position it assumes when a sale has been made in dollars 10 only.

In the upper part of the machine are cylindrical tubes to hold the coin, one for each description of coin to be used and of a diameter such as to receive such coins and closely 15 embrace them and yet leave them free to fall. For distinguishing the tubes the numeral after T indicates the denomination of coins in cents desired in each particular instance. Thus T^5 indicates the tube holding five-cent 20 pieces, and T^{10} the tube holding ten-cent pieces, and so on. The tubes are secured at the base to a support F , Sheet 3, recessed beneath. The sides of support F are provided with 25 grooves F^2 . The latter carry slides E , one slide for each of the tubes carrying pieces below one dollar. The length of each of these 30 slides E is slightly in excess of two diameters of the coin which it assists in feeding, with this exception, that whenever (as in the case 35 of T^{10}) it is desired to make the apparatus capable of dropping either one or two coins at a given discharge, the length of such slide is slightly in excess of three diameters of the coin. The slides E are of the exact thickness 40 of coins and have vertical openings E^2 of the diameter of the tubes under which they work, with the exception of T^{10} , in which case the slide has two openings, each being equal to the inside diameter of T^{10} , openings being located to one end of the slides, substantially 45 as shown. This slide E is operated by a lever L , fixed on shaft S^3 , and operated by a lever L^2 , Sheets 3, 5, and 6, in turn worked by a push-rod L^7 , on whose button L^4 is marked 50 the amount to be deposited in the drawer—i. e., the amount received in payment. If, however, two or more coins are offered in payment, the button representing the smallest piece is pressed.

55 The push-rod L^7 , when button L^4 is pressed, causes lever to rotate L^2 , by means of rods and levers, Fig. 10, which latter causes shaft S^3 to revolve and carry with it lever L , Figs. 3 and 4. This lever comes in contact with cross-piece D , causing slide E to move toward the right, carrying with it every slide on the right.

60 It will be understood that by referring to Figs. 3 and 4 that each slide E has a cross-piece D and that the slides E move in a common groove, and when a slide E is moved toward the right it causes all slides E on the right-hand side to move, while those on the left remain stationary. A spring at the right 65 hand end causes the slides to resume their

normal position—that is, it moves first slide E toward the left. This slide being in contact with next slide E causes it to move toward the left. In this way all slides resume their original position, as shown in Figs. 3 and 4. 70 If, for example, slide E under T^{25} , Fig. 3, is moved toward the right, it being in contact under T^{10} and slide E under T^{10} being in contact with slide E under T^5 causes these slides to move also, while the slide E under T^{50} remains stationary. 75

Each slide E carries its slide B . The latter is just the length of the opening in its slide E , except that of T^{10} , which has two openings E^2 E^3 , in which case slide B is just double the 80 length of the opening and is intended to cover said openings in all cases, except where the coin is to be dropped. Each slide B has a lug B^2 , except that slide which is under the tube T^{10} , and this slide has two lugs B^2 B^3 . 85

The slots H^3 of the arc H are a trifle wider than the lugs B^2 , so as to allow the lugs to pass through them easily.

The push-rods are of denominations as high as the operator may desire as to deposits. In 90 the present instance there are six of them, respectively, marked "10," "25," "50," "100," "200," and "500," standing for such amounts of cash.

The operation of the machine is as follows: 95 If, for example, thirty-cent sale were made, the lever "30," (thirty cents,) Fig. 11, would be pressed. Pin P coming in contact with cam G will cause shaft S^2 to rotate, and with it arcs H , so as to place a slot H^3 opposite the 100 lug B^2 of the slide B , which is under slide E , controlling the coins in cylinder T^5 , thus allowing the slide B to remain under the opening in slide E , thereby preventing the five-cent piece from falling when slides are caused 105 to move. The arc under T^{10} will catch both B^2 and B^3 of T^{10} , there being no slot in this arc at this point, allowing both dimes to fall. The arc T^{25} has a slot, as in the case of the arc under T^5 , which allows its slide B^2 to pass 110 without dropping the twenty-five-cent piece, while the fifty-cent piece is caused to drop. The arcs H are held in position by a pawl, Fig. 9, engaging teeth of segment of controlling arc, Fig. 14. If the change is to be taken 115 out of one dollar, the drawer is closed by pressing push-rod "100," Figs. 1, 3, 4, 8, and 11, which by means of interposed levers, Figs. 9 and 10, causes L to rotate, engaging slide E under tube T^{50} and moves this slide 120 toward the right, carrying with it every slide E to the right of T^{50} . The notches in the arcs H allow the pins B^2 of slide B under T^5 and T^{25} to pass, while the pins in slides B under "10" and "50" are caught and allowing 125 the two ten and the fifty cent pieces to fall into trough J , Fig. 2, as above described. The two lugs B^2 B^3 on slide B under T^{10} are the width of a dime apart, and the one on the left extends down below the one on the right. 130

130

If the slot in arc, Fig. 13, is sufficiently deep to allow both B^2 and B^3 to pass, the openings will remain covered, no coin falling, or may engage B^3 , only allowing one piece to fall, or by engaging both B^2 and B^3 , both will fall, or if the change is to be taken out of a fifty-cent piece, a two, or five dollar bill the method of operation is the same, with the exception that the drawer is closed by pressing the button corresponding to the piece out of which the change is to be taken, and the change will move down through J to the forward portion of the machine, where it can be removed by the operator. The mechanism operated by push-rod "25" and by the push-rod "50" operate in the same way as that operated by the push-rod "100," with the exception that they move every slide to the right of the tube containing the denomination to be deposited—that is, if push-rod "50" were pressed the beveled end L^7 , Figs. 10 and 11, will by a system of levers engage and move cam-arm L^3 , which in turn engages L^2 , causing same to rotate from front to rear, causing arm L , which is fixed to same vertical shaft, to rotate from left to right, Figs 3 and 4, engaging and moving bar D , and with it slide E , as already described. The action of releasing the drawer is as follows: When any lever C is pressed, it rotates shaft S , Figs. 9 and 10, by means of pin and lifts the arm K out of contact with a detent K^2 of the drawer, Fig. 2, and a spring (not shown) presses the drawer open. The oblong hole in lever C , Figs. 9 and 17, engages pin in shaft S , causing shaft to rotate, raising finger K , which is fixed to shaft S , out of detent, as described. The oblong hole allows the shaft to move without carrying with it all the levers C . The drawer may be shut by pressing on any of the push-rods which represent the amount deposited and is pushed until the change drops from the appropriate coin-cylinder. This occurs just before drawer is fully closed, while the instant it closes or after the change has been made the drawer comes in contact with the pawl, which releases teeth in the arc, Fig. 9, allowing all parts of the mechanism to resume their normal position, which they do by means of coiled spring around shaft S^2 . It will be seen by referring to Figs. 10 and 11 that push-buttons can only be moved about one inch when button comes in contact with drawer, which is closed by further pressure of button. This independent movement of one inch of push-button allows cam end of rod L^7 to operate system of levers attached to rear of drawer, engaging and rotating lever L , as already described.

60 The mechanism for making the change where the sale is for more than one dollar is as follows, (see more particularly Sheets 1, 2, 3, and 4.) The tube containing the dollar has four slides U , Fig. 4, each the thickness of a 65 dollar, operated by arms R^4 or R^5 , these arms

being pivoted at R^6 , Fig. 5, allowing one to move independently of the other. The arm R^4 is pivoted to sleeve R by screw R^7 and is engaged by strap R^8 , provided with arm R^3 . Screw R^7 projects into oblong holes in R^4 , so much longer than the diameter of the screw as to allow R^4 to turn one space—i. e., a distance corresponding to a division of controlling arcs H , Sheet 7—before engaging screw R^7 , Fig. 6. The strap at end of R^3 is prevented from rotating around shaft S^2 by guide R^2 , fixed to bottom of machine. V^3 is a segment fixed to end of sleeve R . The latter is free to turn on shaft S^2 and has in this instance five cams worked by levers corresponding to one, two, three, four, and five dollars, respectively, marked on buttons of levers C . S^6 is a coiled spring for throwing sleeve R back to its original position when the drawer is closed, as explained later. V^2 is a segment similar to V^3 , but fixed to shaft S^2 . The middle disk V is fixed to the frame of the machine. Catch Z , fixed to disk V^3 , Fig. 6, in its original position rests in slot of V and engages the one tooth in the face of V^2 . This is constructed in this way so when V^3 is moved one or more spaces V^2 is moved one space only and released by passing out of slot in disk V . This movement of one space carries all of the arcs which control the orifices of the tubes containing coins one space—that is, it brings spaces numbered "2," Figs. 16, 17, 18, and 19, opposite pins B^2 , in which position no coin is released, unless arcs are further moved by lever C of a denomination less than one dollar. $Catch Z^3$ is to hold segment V^3 , arms R^4 and R^5 being attached to segment V^3 by means of sleeve R , Figs. 5 and 6. The catch Z^2 engages the teeth V^2 . Arm R^5 is operated by lever L^6 , Fig. 4, which is caused to rotate by arm L^2 and cam L^7 when drawer is being closed by pressing push-button marked with the denomination "\$2.00." The arm R^3 is similarly operated by the push-rod L^5 , Fig. 11, and arm R^3 imparts to the arm R^4 a lateral movement—viz., causes it to move from left to right, Fig. 5, when drawer is being closed, by pressing button L^4 of five-dollar denomination. Arm L^5 is pivoted to bottom of drawer, extending out for that purpose, Fig. 11. When drawer is being closed, by pushing upon push-rod L^4 , bearing the one, two, or five dollar mark, cam-face on end of arm L^5 is pushed to the left-hand side by means of cam-rod L^7 and levers attached to back of drawer and engages lower end of arm R^3 , moving it to the left and arm R^4 to the right, Figs. 5 and 6, engaging and moving one of the slides V^2 , depending upon the position of R^4 —that is, upon the lever C of the dollar denomination which has been pressed. Slide U^3 , Fig. 6, extends to and rests against end of slide E under T^{20} , and since this slide rests against slide E under T^{25} and slide of T^{25} rests against slide T^{10} and slide E of T^{10} rests

against slide E of T⁶ it follows that if slide V³ is moved toward the right all the slides E will be moved toward the right. Each of the slides U (below the tube containing dollars) has a catch U². The catch of top slide engages base which supports coin-tubes, and the catch of each succeeding slide being located to the right and engages the slide above. The arm R⁴ may engage any of the four catches V². The operation of this mechanism for getting this change is as follows: The lever C for one dollar is pressed and engages its cam G, which is fixed to sleeve R, and thereby causes the latter to move through one space. The arms R⁴ and R⁵ will up to this point remain at rest. This is due to oblong hole R⁸ allowing pin R⁷ to move one space before engaging. The segment V³, connected to sleeve R, has passed through one space. The catch Z has engaged the tooth of segment V² and has caused the shaft S² and the arcs H to move through one space. The second space on the arcs H are slotted, allowing lugs B² of the slide B to pass through the slots in the arcs, and no change out of any of the tubes to the right of the dollar is obtained. As before mentioned, the arms R⁴ and R⁵ have not moved and rest on catches U² of the first (bottom) and fourth (top slides) U, respectively. Now if the change is to be taken out of two dollars, (a two-dollar bill,) then on closing the drawer the push-button "\$2.00" is pressed, which latter engages arm L³ by a system of levers, as before explained, which moves arm R⁶, and the latter in turn moves arm R⁵, which pushes lower slide U, by means of catch U², and releases slide U from the slide above and pushes it forward until one dollar is dropped into trough J. If five dollars (currency) is given in payment, then the push-button "\$5.00" is pressed in closing the drawer, and this button pushes to the left cam L⁵, Fig. 11, which latter engages the lower end of arm R³, pushing R³ toward the left (see Figs. 5 and 6) and pushing arm R⁴ toward the right, and thereby pressing the catch of U² of the top slide U, which carries with it the three lower slides U beneath it, Fig. 4, and thereby drops four dollars. If the sale is two dollars or three dollars or four dollars, the method of operation is the same, except that for each additional dollar the arms R⁴ and R⁵ rotate through one space, as actuated by the appropriate levers C. If the sale is two dollars, the arm R⁵ will, if caused to move toward the right, come in contact with slide U³, which latter operates the slides under T⁵⁰, T²⁵, T¹⁰, and T⁵ only. The same is true when the sale is five dollars. The arms R⁴ will come in contact with slide U³. If the amount is one dollar and a fraction of one dollar, the dollar-lever is pressed, as before, with the same result as taking up space in the slot (or hole) R⁸ up to screw R⁷ and turning shaft S² through one space—viz., the one-dollar

space on the arc H. Now if the sale is a dollar and thirty cents, the thirty-cent lever is now pressed, carrying the shaft S² and arcs H to the sixth space. The segment V², fixed to shaft S², and the catch Z² are carried forward, Fig. 7, engaging the first tooth in the segment V³, which has been previously carried under Z² by the dollar-lever having been pressed and carrying segment V³ one space, together with sleeve R and arms R⁴ and R⁵ through one space, causing arm R⁴ to rest on the third catch U² and arm R⁵ resting on the slide U³. If now two dollars is given in payment, the "\$2.00" push-button is pressed in, closing the drawer, and arm R⁵ is caused to move forward, carrying slide U³, which latter moves the slides E under T⁵⁰, T²⁵, T¹⁰, and T⁵ only. If, on the other hand, five dollars currency is given for the one-dollar-and-thirty-cent sale, the push-button "\$5.00" is pressed in, closing the drawer, causing arm R⁴, which is resting on the catch of the third slide, (third from bottom) to carry this slide and those below it forward and also slides E under the other tubes on the right, Fig. 4, thereby causing in this event three dollars and seventy cents to fall into trough J. (Reference being had in this connection to the description of the thirty-cent sale heretofore given.)

It will be noted that if segment V³ moves any number of spaces (from one to four) it carries segment V² only one space, (see Figs. 5, 6, and 7,) catch Z² holding it in place. On the other hand, though segment V² may move any number of these spaces it will carry segment V³ only one space. It is to be borne in mind that the segment V² is held in position by catch N engaging teeth of arc H⁵, as already explained. (See Fig. 9.)

For the better understanding of the operation of the segments V² and V³ and their accompanying parts this detailed description is submitted. When the segment V³, Sheet 4, is moved by sleeve R through the agency of a given cam G, it (the segment V³) will move segment V² one space forward by means of the spring-catch Z, which is resting in the adjacent notch of segment V². As soon as the catch has moved the segment V² thus this catch is thrown out of engagement with the notch of segment V² by means of the incline on the middle disk V, which latter moves the catch out of such engagement. It will be understood that the drawer being open the spring-pawl N is engaging the teeth of the arc H⁵, and as the segment V² was moved by the catch Z the teeth of arc H⁵ duly slip by the pawl N, but prevent retraction of the arc H⁵ (and of the arc H) until the drawer is closed. While the segment V³ has moved the segment V² only one space, it is itself moved one or more spaces, according to the lever that is pressed, bringing one of the teeth of segment V³ under catch of spring Z².

This catch Z^2 will hold segment V^3 in position—that is, to prevent its retraction during a given operation of the machine. When a lever corresponding to any one of the sums less than one dollar is pressed, it causes segment V^2 to move the requisite distance for moving the arcs H the necessary number of spaces and will at the same time through the agency of the spring-catch Z^2 , which is fixed to segment V^2 , move the segment V^3 one space and then liberating the segment V^3 from positive connection with segment V^2 by raising the catch Z^2 on the disk V in the same way as specified in relation to catch Z . A further spring-catch Z^3 is present and is fixed at Z^4 to the disk V , and its free or latch end rests (after the dollars have been registered and before the cents have been registered) upon the outer side of the latch end of catch Z^2 and over the teeth of segment V^3 . Now when segment V^2 is moved upward it carries catch Z^2 upward and from under the catch of the spring Z^3 and out of engagement with the tooth of segment V^3 . The catch end of Z^3 now descends and engages the teeth of segment V^3 and prevents its retraction. When the drawer is closed, Fig. 9, it disengages the pawl N from the teeth of arm H^5 , allowing the spring S^5 to return shaft S^2 , and with it arcs H and segment V^2 to their original position. The spring-catch Z^2 , (which is fixed to disk V^2 , disk V^2 being fixed to and rotates with shaft S^2), passing under the spring-catch Z^3 , disengages the latter from the teeth of segment V^3 and allows the segment V^3 and arms R^4 and R^5 to resume their original position, which they will do by means of coiled spring S^6 .

Since the initial position of the arcs—that is, the position they take every time after change has been made—is such as to engage the lug B^2 of each slide B , change may be made for any piece of money by pressing "no-sale" lever C , which does not cause shaft S^2 to rotate—that is, allows arcs H and arms R^4 and R^5 to remain stationary—and closing drawer by push-button denoting the amount of the piece for which change is to be had. For example, if change for one dollar is desired the "no-sale" lever is pressed, which does not move the arcs H , and by pressing push-button "100" in closing the drawer every slide is engaged, dropping "50," "25," two "10," and "5."

What I claim as new and of my invention, and desire to secure by Letters Patent, is—

1. In a change-making cash-register, the combination of coin-receptacles, separating-slides for operating and controlling said receptacles, and discharging-slides carried by said separating-slides, substantially as described.
2. The combination of separating-slides, discharging-slides carried by said separating-

slides, push-rods, fulcrumed levers, and controlling-arcs operated by said push-rods. 65

3. The combination of finger-levers, separating and discharging slides, push-rods operating said slides, arcs governing said slides and coin-receptacles controlled by said slides. 70

4. The combination of coin-receptacles, separating and discharging slides, push-rods operating said slides and a cash-drawer to which the push-rods are attached.

5. The combination of finger-levers, controlling-cams operated by said levers, a cash-drawer, push-rods connected to the cash-drawer, coin-receptacles and operating-slides under the coin-receptacles. 75

6. In a change-making cash-register, a combination of receptacles, a series of operating-slides, delivering-slides carried by said operating-slides, substantially as shown and described. 80

7. In a change-making cash-register, a combination of coin-receptacles, coin-operating slides having openings corresponding to diameter of coin, delivering-slides controlling said operating-slides, substantially as shown and for the purpose specified. 90

8. In a change-making cash-register, a combination of coin-receptacles, coin-separating slides, delivering-slides carried by said coin-operating slides, controlling-cams, and push-rods operating said slides and cams, substantially as shown and for the purpose specified. 95

9. The combination of cams, levers for operating said cams, lever-arms controlled by said cams, a coin-receptacle and four slides operating under said receptacle, said slides being operated and controlled by said lever-arms. 100

10. The combination of movable and stationary disks, lever-arms controlled by said disks, coin-receptacles, and slides controlled by said lever-arms and operating beneath said receptacles. 105

11. The combination of movable and stationary disks, controlling-arms governed by said disks, delivering-slides operated by said arms and cams and push-rods governing said controlling-arms. 110

12. In a change-making cash-register, the combination of finger-levers fulcrumed as shown, pins in lever-arms, shaft carrying and controlling arcs, pins in finger-levers for operating said cams, substantially as shown and for the purpose specified. 115

13. In a change-making cash-register, a shaft, key-levers fulcrumed on said shaft, pins on said levers, a second shaft, cams and controlling-arcs having projections fixed on said shaft, and coin separating and delivering slides, said slides being governed by said arcs, substantially as shown and described. 120

14. The combination of finger-levers, fulcrumed as shown, a shaft, cams fixed on said

6
shaft and engaged by said finger-levers, operating and delivering slides, controlling-
arcs fixed to said shaft and controlling said
slides, a cash-drawer and push-rods connected to said drawer, said push-rods operating
said slides.

15. The combination of finger-levers ful-
crumed as shown, pins in said levers, a shaft,
controlling-cams and governing-arcs fixedly
adjusted on said shaft, said arcs having slots
or recesses.
